UNITED STATES PATENT OFFICE.

ENGELBERT LUDESCHER, OF CHICAGO, ILLINOIS.

PORTABLE ELECTRIC LAMP.

1,248,688.

Specification of Letters Patent.

Patented Dec. 4, 1917.

Application filed May 16, 1917. Serial No. 169,057.

To all whom it may concern:

Be it known that I, ENGELBERT LUDESCHER, a citizen of the United States, residing at Chicago, in the county of Cook and State of Illinois, have invented a new and useful Portable Electric Lamp, of which the following is a specification.

The present invention appertains to portable electric lamps, and aims to provide a novel and improved device of that character which can be used as a flash light, lantern, electric torch or candle, and the like.

It is the object of the invention to provide a combination lamp of the nature indicated embodying a novel assemblage of the component elements, whereby the lamp is particularly useful and efficient for various purposes, and may be used in the household, in barns, garages, or the like, and upon vehicles, although it is to be understood that the use of the lamp is not limited.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:—

Figure 1 is a side elevation of one form of lamp construction, portions being broken away.

Fig. 2 is a sectional detail thereof showing the reflectors brought together whereby the device serves as a flashlight.

Fig. 3 is a fragmental view of a second form of the invention, portions being shown in section.

Fig. 4 is a perspective view of a cover to inclose the sides of the reflectors.

Fig. 5 is an elevation of another variation, showing the structure in the form of a lantern, portions being broken away.

Fig. 6 is a perspective view of a further modification.

Fig. 7 is a diametrical section of the modified form shown in Fig. 6 with the reflector in position to provide a lantern.

Fig. 8 is a similar view with the reflector adjusted to provide a flash light.

Fig. 9 is a perspective view of a simplified form.

Referring to Figs. 1 and 2, there is illustrated therein, a tubular handle or casing 1, such as is commonly used in portable flashlights, for holding the battery. Removably attached to one end of the handle or casing 1 is a head 2, which is enlarged, and provided with a conical or convexed reflector 3 carrying at its apex or central portion, an electric bulb 4.

Threaded upon the head 2, preferably upon the larger diametered portion thereof, is a ring 5 having an outwardly offset portion or seat 6 in which is seated the inner edge of a transparent shell 7 of glass or other suitable material, and which, as illustrated, is of tapered or frusto-conical form. The larger diametered portion of the shell 7 seats against the ring 5, and a substantially conical or dished reflector 8 is disposed within the smaller diametered portion of the shell 7 and has its rim seating against the corresponding edge of the shell. The reflector 8 has an opening 9 at its apex or central portion, and a lens 10 is seated against the rim of the reflector 8 across the mouth thereof. A ring or band 11 surrounds the smaller diametered portion of the shell 7 and edges of the reflector 8 and lens 10, and has an inturned flange or lip 12 overlapping the lens 10 to hold said lens and reflector 8 against the shell 7. A plurality of rods or stays 13 have their outer ends soldered or otherwise secured to the ring 11, and their inner terminals extend slidably through sleeves or apertured members 14 soldered or otherwise secured to the ring 5. Nuts 15 are threaded upon the inner terminals of the rods 13 and bear against the sleeves 14, whereby when the nuts are tightened, the rings 11 and 5 are drawn toward one another to clamp the shell 7 between the rings, with the rim of the reflector 8 and edge of the lens 10 clamped between the shell 7 and flange or lip 12.

The ring 5, shell 7, ring 11, reflector 8 and lens 10 are thus rigidly united to form an adjustable and removable unit, and the parts of said unit can be readily separated, for pur-

pose of cleaning, repair or replacement, by unscrewing the nuts 15.

In use, by unscrewing the ring 5 from the head 2, to remove the shell 7, reflector 8 and corresponding parts, the handle or casing 1 with its head 2 and bulb 4 will provide an electric torch or candle. The circuit of the bulb 4 can be controlled by any suitable switch (not shown) in accordance with common practice. When it is desired to use the device as a flashlight, the ring 5 is threaded onto the head 2 sufficiently to bring the reflector 8 against the reflector 3, as seen in Fig. 2, thereby projecting the bulb 4 through the opening 9 into the reflector 8, and said reflectors being brought together, will close the space between them, whereby all of the light rays pass through the lens 10. This will provide a flashlight which can be used in the manner of ordinary flashlights, the light rays being concentrated by the reflector 8 and lens 10. By unscrewing the ring 5 slightly, as seen in Fig. 1, to remove the reflector 8 the desired distance from the reflector 3, the device will now serve as a lantern, since the bulb 4 will be disposed between the apices of the two reflectors and the light can radiate in all directions between the reflectors through the shell 7, a portion of the light rays also passing through the opening 9 and lens 10. This provides a desirable lantern, and the light can be controlled by adjusting the reflector 8 to and from the bulb 4 by rotating the ring 5 above the head 2. The device can therefore be readily adjusted for use as an electric torch or candle, a lantern or a flashlight, whichever is desired.

Fig. 3 illustrates a simplified construction. The handle or casing 1^a has the ferrule or head 2^a provided with the convexed or substantially conical reflector 3^a carrying the bulb 4^a at its apex. A ring 5^a is threaded upon the ferrule or head 2^a, and the transparent shell 7^a seats at one end or edge against the shoulder of the head 2^a surrounding the reflector 3^a. The rim of the second reflector 8^a seats against the other end or edge of the shell 7^a and the lens 10^a seats against the rim of said reflector 8^a. The reflector 8^a has a central opening 9^a through which the bulb 4^a projects partially. A ring 11^a fitted upon the outer end portion of the shell 7^a has a flange or lip 12^a inturned to overlap the lens 10^a, and a plurality of rods or stays 16 are soldered or otherwise secured to the rings 5^a and 11^a. When the ring 5^a is threaded upon the head or ferrule 2^a, this brings the shell 7^a against said head, to clamp the shell between the head 2^a and ring 11^a. When the ring 5^a and corresponding parts are removed from the head 2^a, the device serves as an electric torch or candle, and when said parts are applied, the device 65 serves as a lantern. A flexible cover or band

16 of leather, cloth, or other suitable material, can be wrapped around the shell 7^a to inclose the reflectors, the overlapped ends of said cover being detachably connected by means of snap fasteners 17, whereby the light rays can only pass through the lens 10^a, to serve as a flashlight.

The device as shown in Fig. 5 is of the lantern type, having the casing or body 1^b provided with the removable bottom or cover 1^c to enable the battery to be placed within and removed from the casing 1^b. The casing is provided at its upper surface with a boss or raised portion 2^b having the substantially conical reflector 3^b upstanding therefrom and carrying the electric bulb 4^b at its apex. The transparent shell 7^b is provided at its inner end with a contracted threaded portion 5^b to screw onto the threads of the boss 2^b whereby to removably attach said shell to the casing or body, and the cap 10^b of the lantern is provided with threads to screw into the outer contracted threaded end of the shell 7^b. The cap 10^b has a depending conical reflector 8^b projecting toward and adjacent to the bulb 4^b, whereby the two reflectors which project toward one another with the bulb therebetween to reflect the light to all sides. A bail or handle 18 is connected to the cap 17 for conveniently carrying the lantern.

In the structures shown in Figs. 6, 7 and 8, the numeral 1^d represents the body or casing, for holding the battery, and which may be of any suitable size or shape, being provided in this case with a flat disk-shaped reflector 3^d carrying the bulb 4^d at its center. A ring 5^d is threaded upon the casing 1^d and has adjustably connected thereto the stays 13^d which are connected at their outer ends with the ring 11^d. The ring 11^d holds the lens 10^d and conical reflector 8^d. The transparent shell 7^d between the rings 5^d and 11^d can be used between. By adjusting the ring 5^d, the reflector can be moved outwardly away from the bulb, as seen in Fig. 7, whereby to provide a lantern, or the reflector can be moved inwardly to surround the bulb, as seen in Fig. 8, to provide a flash light.

The simple form of the invention shown in Fig. 9 embodies the rings 5^e and 11^e connected by stays 13^e and having a transparent shell 7^e therebetween, the ring 5^e holding a disk-shaped reflector 3^e having a central bulb 4^e, and the ring 11^e holding a lens 10^e.

Having thus described the invention, what is claimed as new is:—

An electric lamp embodying a casing, an electric bulb carried thereby, a ring adjustable on the casing, a transparent shell surrounding the bulb and having one end seating against said ring, a reflector having its rim seating against the other end of the casing, the reflector projecting into the casing 130

and having an opening for the passage of the bulb, a lens extending across said reflector and seating against the rim thereof, a second ring surrounding the second mentioned end of the shell and having a portion overlapping the lens, and means connecting the two rings for holding the shell, reflector and lens therebetween.

In testimony that I claim the foregoing as my own, I have hereto affixed my signature 10 in the presence of two witnesses.

ENGELBERT LUDESCHER.
